APPARATUS FOR USE IN MAKING INSOLES

George F. C. Burke, Fairhaven, Mass., assignor to United Shoe Machinery Corporation, Flemington, N. J., a corporation of New Jersey

Application February 24, 1950, Serial No. 145,963

10 Claims. (Cl. 12—17)

1
This invention relates to apparatus for use in making insoles and particularly to apparatus for use in attaching pieces of canvas to insole-shaped matrices.

In using machines of the type disclosed in United States Letters Patent No. 2,494,578, granted January 17, 1950, in the name of Hans C. Paulsen, canvas is secured to one end of an insole-shaped matrix of the kind disclosed in United States Letters Patent No. 2,577,750, granted December 11, 1951, in the names of Stanley M. Griswold and Hans C. Paulsen. The matrix is provided near its rear end with a sharp point or tang on which a piece of canvas is impaled so that the canvas can be held taut on the matrix when it is presented to the machine. The canvas may be pressed on the tang by one of the digits of the operator's hand, usually the thumb, but in doing this constantly in the course of a day's run it has been found that the operator's thumb became badly lacerated with danger of infection.

Accordingly, it is an object of this invention to provide means for use in attaching the canvas to the matrix by which contact of any part of the operator's hand with the tang is avoided.

To this end the apparatus comprises a fulcrum or rest to engage the lower side of the matrix at a distance from its rear end and an abutment for engaging the canvas near the tang so that, by depression of the forepart of the matrix, the canvas will engage the abutment and the tang be forced through it. The operator can then tension the canvas forwardly with respect to the matrix, thus preparing it for presentation to the machine.

Preferably a U-shaped gage is provided to locate the rear end of the matrix longitudinally and laterally with respect to the abutment so that when the forepart thereof is depressed the tang will be in proper relation to the abutment to cause the canvas to be pressed upon the tang without contact of the tang with the abutment.

The abutment may be variously formed. In one instance it is illustrated as a member having a hole, the portions of which member around the hole engage the canvas while the tang enters the hole. An upwardly and outwardly inclined surface adjacent to the abutment may be provided to steer the matrix into position beneath the abutment and against the gage.

In another instance the abutment as illustrated is in the form of a rotatably mounted, grooved wheel, the gage insuring that the matrix will be so located that the tang will be opposite the groove in the wheel and that the periphery of

2
the wheel will engage the canvas on each side of the tang and press it thereon.

In the drawings,

Fig. 1 is a side elevation of the apparatus in use;

Fig. 2 is an enlarged sectional view of parts shown in Fig. 1 showing how the canvas is attached to the tang by pressing it upon the abutment;

10 Fig. 3 is a side elevation, partly in section, of a modified form of the apparatus; and

Fig. 4 is an enlarged perspective view of the apparatus shown in Fig. 3, taken in the direction of the arrow in that view.

15 Referring to Fig. 1, a supporting shaft 10 is provided adjacent to the machine and carries a split block 12 which is clamped to the shaft by a cap screw 14. The screw 14 also passes through a plate 16 which is adjustable about the shaft

20 while the block 12 is adjustable about the shaft 10, both being held in place by tightening the screw 14. The plate 16 has a downturned end portion 18, the angle between the portions 16 and 18 serving as a fulcrum to support a matrix

25 M which is sole shaped. A piece of canvas C is placed on the matrix and its rounded rear end placed against a V-gage 20 having a pair of integral lugs 21 secured to the plate 16 by screws 22. The gage 20 locates the matrix longitudinally and laterally so that a tang T near the rear end of the matrix is beneath an abutment 24 having a vertical counterbore 26 (Fig. 2). Above the counterbore is a smaller bore threaded to receive a screw 28 by which the abutment 24 is secured

30 to a bracket 30 held by screws 32 to the plate 16. 35 As shown in Fig. 2, the tang is upwardly and rearwardly inclined and is struck out from a plate P which is secured by nails in the bottom of a recess in the matrix M, the recess being of a depth such that the end of the tang is substantially flush with the adjacent flat face of the matrix. The tang is thus protected from injury and requires the canvas to be depressed into the recess in order to cause it to be caught on the tang so that when the canvas is pulled toward

40 the front or toe end of the matrix the canvas will slip down on the tang and be securely held thereby.

45 Downward pressure on the forepart of the matrix by the operator causes the matrix to fulcrum at the angle between the parts 16 and 18 of the plate and causes the canvas to be pressed over the tang T by the peripheral portion of the abutment surrounding the counterbore 26, the

50 said peripheral portion being small enough to

55

enter the depression in the matrix in which the tang is located. Due to the inclined position of the matrix, the rear portion of the abutment presses the canvas more deeply into the recess at the rear of the rearwardly inclined tang to insure that the canvas will catch upon it and be securely held against movement toward the toe end of the matrix, a toeward pull on the canvas serving only to cause the tang to penetrate farther into the canvas. The matrix is then removed and presented to the machine.

To facilitate the introduction of the matrix beneath the abutment, the abutment may have a forward projection having a downwardly and rearwardly inclined surface 36 so that if the matrix engages the surface it will be guided under the abutment.

In Figs. 3 and 4 a modified form of abutment is illustrated consisting of a yoke 38 carrying a threaded stud 40 which extends through a bracket 31 similar to the bracket 30 and is held by a nut 44. Freely journaled in the yoke 38 is a wheel 46 having a groove 48 in its periphery. A forward extension of the yoke 38 is bent downwardly and rearwardly to form a guiding surface 37 similar to the surface 36 on the abutment 24. The outer portions of the periphery of the wheel 46 (Fig. 4) are beveled so that their points of contact with the canvas will be near the groove 48. Thus the pressure on the canvas will be concentrated at each side of the tang to cause it to penetrate the canvas. If, while inserting the matrix into the apparatus, the canvas engages the wheel 46, it will turn and permit easy passage of the matrix into contact with the gage 20. In the construction shown in Figs. 3 and 4 the gage 20 and the plates 16 and 18 are like those shown in Fig. 1. The matrix M with the canvas C is guided by the surface 37 or the surface of the downturned portion 18 of the plate into engagement with the gage 20 by which it is located laterally and longitudinally so that when the forepart of the matrix M is depressed the tang T will enter the groove 48 of the wheel 46 and the periphery of the wheel will engage the canvas at each side of the tang and cause it to penetrate the canvas.

Having thus described my invention, what I claim as new and desire to secure by Letters Patent of the United States is:

1. Apparatus for use in attaching canvas to an insole-shaped matrix having a tang near its rear end comprising a fixed plate forming a fulcrum for the matrix, and a recessed abutment above and attached to the plate and arranged to engage the canvas adjacent to the tang and to cause the tang to penetrate the canvas by turning of the matrix on the fulcrum while the tang enters the recess.

2. Apparatus for use in attaching canvas to an insole-shaped matrix having a rearwardly inclined tang near its rear end comprising a fixed plate forming a fulcrum for the matrix, and a hollow abutment above and secured to the plate and arranged to engage the canvas at the rear of the tang to cause the tang to penetrate the canvas by turning of the matrix on the fulcrum, the tang entering the hollow abutment.

3. Apparatus for use in attaching canvas to a tang on a matrix comprising a plate providing a fulcrum for the matrix, and an abutment above and attached to the plate against which the canvas on the matrix is brought by movement of the matrix about the fulcrum, said abutment having a surface to engage the canvas adjacent to

the tang, having a recess to receive the tang as it is forced through the canvas and having a portion with a downwardly and rearwardly inclined surface to guide the matrix beneath the abutment.

4. Apparatus for use in attaching canvas to an insole-shaped matrix having a tang near its rear end comprising a plate having a fulcrum for the matrix, an abutment above the plate and attached thereto, and a gage fixed to the plate for locating the tang on the matrix with respect to the abutment so that movement of the matrix about the fulcrum will cause the canvas to engage the abutment and be pushed onto the tang.

5. Apparatus according to claim 4 in which the gage is V-shaped and acts to locate the matrix longitudinally and laterally with respect to the abutment as the matrix is brought into contact therewith.

6. Apparatus for use in attaching canvas to a tang on a matrix comprising a plate providing a fulcrum for the matrix and an abutment above the plate and fixed thereto against which abutment the canvas on the matrix is brought by movement of the matrix about the fulcrum, said abutment having a surface to engage the canvas adjacent to the tang and having a recess to receive the tang as it is forced through the canvas.

7. Apparatus for use in attaching canvas to a matrix having a tang comprising a horizontal plate having a downturned end to guide the matrix onto the plate, the angle in the plate providing a fulcrum for the matrix, and an abutment over the plate, the abutment having a recess to receive the tang of the matrix and having portions at each side of the recess to engage the canvas to cause it to be penetrated by the tang as the portion of the matrix outwardly beyond the fulcrum is depressed.

8. Apparatus for use in attaching canvas to a matrix having a tang comprising a horizontal plate having a down-turned end to guide the matrix on to the plate, the angle in the plate providing a fulcrum for the matrix, and an abutment over the plate, the abutment having a recess to receive the tang of the matrix and a portion at the rear of the recess to engage the canvas to cause it to be penetrated by the tang as the forepart of the matrix is depressed.

9. Apparatus for use in attaching canvas to a tang on a matrix comprising a fulcrum for the matrix, and an abutment above the fulcrum in fixed relation thereto against which abutment the canvas on the matrix is brought by movement of the matrix about the fulcrum, said abutment comprising a grooved wheel mounted for free rotation, the groove receiving the tang, and the periphery of the wheel engaging the canvas at each side of the tang and causing the tang to penetrate the canvas when the matrix is moved about the fulcrum.

10. Apparatus according to claim 9 in which there is provided adjacent to the abutment a member having a downwardly and rearwardly inclined surface to guide the matrix beneath the abutment as it is presented to the apparatus.

GEORGE F. C. BURKE.
